PREPARATION OF LIPOPROTEINS

Edward F. Cavanaugh, Wilmette, Ill., assignor to Armour and Company, Chicago, Ill., a corporation of Illinois

No Drawing. Application May 16, 1955,
Serial No. 508,825

10 Claims. (Cl. 260—112)

This invention relates to the preparation of lipoproteins, and more particularly to a process for purifying protein-fatty acid halide condensation products.

The synthesis of conjugated proteins, and especially of lipoproteins, has been developed in relatively recent years. One method of preparing lipoproteins involves condensing a fatty acid halide and a proteinaceous substance in an alkaline medium. This is the well-known Schotten-Baumann procedure. In the co-pending patent application Serial No. 221,541 of Keil, filed April 17, 1951, which issued on December 27, 1955, as U. S. Patent No. 2,728,759, is disclosed an improvement of this Schotten-Baumann procedure which involves treating the proteinaceous substance with hydrogen peroxide prior to reaction thereof with the fatty acid halide to obtain an increased content of fatty acid component in the resulting lipoprotein.

In carrying out this Schotten-Baumann procedure, a portion of the fatty acid halide reacts with the alkali contained in the reaction mixture to form a soap and an inorganic halide. Consequently, the lipoprotein reaction product may be contaminated with the soap and the inorganic salt. Also, such reaction product may contain unreacted alkali.

An object of this invention is the provision of a process for preparing a purified lipoprotein. Another object is the provision of a process for separating soap and salt contaminants of lipoprotein products. Other objects and advantages of this invention will become apparent as the specification proceeds.

In one aspect of this invention a lipoprotein substance, obtained by reacting a proteinaceous substance and a fatty acid halide in an alkaline medium and dehydrating the resulting reaction product, may be purified by a process which involves mixing such lipoprotein with an organic fat solvent having a specific gravity higher than that of the lipoprotein. The mixture of this organic fat solvent and the lipoprotein substance should be achieved in a substantially anhydrous system, and the lipoprotein substance should be maintained at an acidic reaction in such solvent mixture. The acidification of the lipoprotein substance converts the soap contaminant thereof to the free fatty acid, and results in the formation of a salt therein. When this mixture is brought to an equilibrium state, there is produced a heterogeneous solvent system, including a salt phase subjacent to a fat solvent phase, and a lipoprotein phase superimposed upon such fat solvent phase. Then, the lipoprotein phase may be separated from the other phases in this heterogeneous system to provide a substantially purified lipoprotein product.

The lipoprotein substance employed in this purification procedure may be prepared by reacting any proteinaceous substance with any fatty acid halide. The term "proteinaceous substance" employed herein means derived proteins such as proteoses, polypeptides and peptones, as well as whole proteins. Preferably, this fatty acid halide reactant contains from 1 to 22 carbon atoms, and espe-

2

cially desirable results are obtained with fatty acid halides containing from 12 to 18 carbon atoms. Also, this fatty acid halide reactant can be derived from a mixture of fatty acids, such as are prepared from tallow and soya bean. As suitable fatty acid halides for use in preparing this lipoprotein substance, I mention, for example, the halide derivatives of such fatty acids as oleic, palmitic, lauric, capric, stearic, etc. The halide component of this fatty acid halide reactant may be bromine, fluorine, chlorine, etc. but better purification of the lipoprotein substance can be achieved when it is derived from a fatty acid chloride reactant.

The proteinaceous substance and the fatty acid halide may be reacted in an alkaline medium to form a lipoprotein reaction product. The reaction mixture should include an alkali having a cation capable of reacting with the anion of an acid to form a salt. Better results are obtained when an inorganic alkali is included in the reaction mixture, and an especially desirable purification of the lipoprotein reaction product is achieved with an alkali having an alkali metal cation, e. g. sodium, potassium, etc.

The lipoprotein reaction product should be dehydrated while being maintained at a substantially neutral or alkaline pH. I have found that the acidification of such reaction product prior to drying apparently increases the melting point and viscosity thereof such that it is difficult to obtain the lipoprotein substance in a substantially anhydrous form. Preferably, the reaction product is maintained at a pH of at least pH 6.5 during this drying step, and especially desirable dehydration is obtained when the reaction product has a pH of at least pH 7.5. The drying of this lipoprotein reaction product may be obtained by such methods as evaporation, lyophilization, etc.

The dehydrated lipoprotein substance may contain such contaminants as soap, residual alkali and a salt. Preparatory to purification, the dehydrated lipoprotein substance may be pulverized to produce greater exposure of the contaminants therein to the acidifying agent and to the organic fat solvent. The pulverizing of this lipoprotein substance may be obtained by a method such as comminution, grinding or milling.

The pulverulent lipoprotein substance can be mixed with the organic fat solvent to form a substantially anhydrous solvent mixture. This mixing operation may be carried out by charging the lipoprotein substance into a suitable vessel, and then charging into the vessel the organic fat solvent. The mixing of the lipoprotein substance and the fat solvent may be achieved by pumping, stirring, churning, etc.

The acidification of the lipoprotein substance may be obtained by contacting this solvent mixture with an anhydrous acid which is dispersible in such solvent mixture. By dispersible, I mean that the anhydrous acid should be either soluble in the organic fat solvent or in the gaseous state such that it may be bubbled through the solvent mixture. I have found that substantially all of the soap contaminant of the lipoprotein substance may be converted to the free fatty acid by infusing into the solvent mixture acid in such amount as to adjust the pH of the lipoprotein substance to less than about pH 5.5. I prefer to obtain conversion of the soap contaminant to the free fatty acid by adjusting the pH of the lipoprotein substance to about pH 5.0, and usually a pH within the range of pH 5.5 to 4.5 is sufficient to obtain conversion of the soap contaminant to the free fatty acid. As acids suitable for mixing with the solvent mixture to obtain conversion of the soap contaminant to the free fatty acid, I mention, for example, mineral acid anhydrides, e. g. hydrochloric, sulfuric, sulfurous and phosphoric, and organic acids, e. g. oxalic.

As mentioned hereinbefore the organic fat solvent should have a specific gravity higher than that of the lipoprotein. Experience to date has shown that the specific gravity of a lipoprotein is generally less than about 1:3. Also, I have found that the specific gravity of a lipoprotein is usually more than 0.8, and consequently the specific gravity of a lipoprotein is more often between about 1 to 1.1. Thus, this organic fat solvent should have a specific gravity higher than about 0.8 to 1.3. On the other hand, the specific gravity of this organic fat solvent should be less than that of the inorganic salt. Consequently, the specific gravity of such solvent may be less than about 1.9 to 2.7. I mention, for example, such suitable organic fat solvents, together with their specific gravities, as: chloroform 1.498, carbon tetrachloride 1.595, trichlorethylene 1.456, dioxane 1.034, chlorobenzene 1.107, and ethylene dichloride 1.257.

The ratio of organic fat solvent to lipoprotein substance included in this solvent mixture may be increased in accordance with an increased concentration of contaminant substances contained in such lipoprotein substance. I have found that the dehydrated lipoprotein product generally contains not more than 40% by weight of such contaminant substances, and more often the concentration of contaminants therein is less than 25% by weight. However, it is seldom that the concentration of these contaminants in the lipoprotein product is less than about 10%, but in more efficient operation it may be possible to obtain a concentration of contaminants therein of about 3 to 6%. Consequently, in the usual practice a ratio of fat solvent to lipoprotein substance of at least about 2 is suitable for carrying out this purification, and for practical considerations a ratio of fat solvent to lipoprotein substance of less than about 10 is convenient.

After dispersing the lipoprotein substance in the organic fat solvent, the resulting solvent mixture may be settled to obtain an equilibrium state therein, and to provide the heterogeneous solvent system. In this heterogeneous system, the contaminant free fatty acid dissolves in the organic fat solvent forming a layer subjacent to the lipoprotein phase and superimposed upon a salt phase. The lipoprotein phase may be separated from the other phases by draining, skimming, etc. In the former method, the subnatant organic solvent and salt phases can be drained from the bottom of the mixing vessel, and the residual lipoprotein recovered from the bottom of the vessel. The latter separation method involves skimming the lipoprotein layer from the top of the mixing vessel. The residual organic fat solvent may be removed from the separated lipoprotein by evaporation, etc.

This invention can be more fully illustrated by the following specific examples:

Example I

To 300 gm. of gelatin, dissolved in an aqueous solution of sodium hydroxide having a pH of about 9.0, was added stearyl chloride. This reaction mixture was acidified to a pH of 5.4 and dehydrated. The resulting lipoprotein product was analyzed and found to contain 66% of lipoprotein, 20% of sodium chloride and 14% of free fatty acid.

This lipoprotein product was suspended in 3000 cc. of ethylene dichloride. After settling the mixture to obtain an equilibrium state, the supernatant lipoprotein layer was separated from the other layers by skimming. The skinned lipoprotein layer was dried by evaporation. This dry product was analyzed and found to contain 96% of lipoprotein and 4% of sodium chloride. The subnatant salt layer was also separated from the purification mixture, and upon analysis was found to contain 85% of sodium chloride.

Example II

A lipoprotein product, obtained by reacting gelatin with

a fatty acid chloride was prepared. This lipoprotein product, had a pH of 5.3, and its composition was as follows:

	Percent
5 Lipoprotein	76.9
Sodium chloride	16.6
Free fatty acid	6.5

This lipoprotein product, in the amount of 10 gm., was suspended in 100 cc. of trichloroethylene and the resulting mixture was settled to form three phases. The supernatant lipoprotein phase was separated by skimming, and the skinned lipoprotein dried by evaporation. The dry product was analyzed and found to have the following composition:

	Percent
Lipoprotein	92.6
Sodium chloride	7.4

Example III

20 A reaction product of lard flake fatty acid chlorides and gelatin was prepared. This lipoprotein product had a pH of 7.7, and the following composition:

	Percent
25 Lipoprotein	48
Free fatty acid	22.3
Sodium chloride	25.7

This lipoprotein product, in the amount of 100 gm., was suspended in 3000 cc. of ethylene dichloride. Gaseous hydrochloric acid was added to this suspension until a pH of 4.7-5.0 was obtained. After settling, the supernatant solvent and lipoprotein layers were separated from the subnatant salt layer by decantation. The decanted supernatant layers were separated by filtration. The separated lipoprotein layer was dried by evaporation, as was the subnatant inorganic salt layer. The dry lipoprotein product was analyzed and found to have the following composition:

	Percent
40 Lipoprotein	92
Sodium chloride	5.5
Free fatty acid	2.5

The purified lipoprotein product was again suspended in ethylene chloride, and the lipoprotein layer separated from the resulting heterogeneous system. The separated lipoprotein layer was analyzed and found to be free from fatty acid contamination and practically free of inorganic salt.

50 While in the foregoing specification various embodiments of this invention have been set forth and many details thereof elaborated for the purpose of illustration, it will be apparent to those skilled in the art that this invention is susceptible to other embodiments and that many of these details can be varied widely without departing from the basic concept and spirit of this invention.

I claim:

1. In a process for preparing a lipoprotein, wherein a proteinaceous substance and a fatty acid halide are reacted in an alkaline medium to form a lipoprotein substance, the steps of forming a substantially anhydrous mixture comprising said lipoprotein substance and an organic fat solvent having a specific gravity higher than that of the lipoprotein to form a heterogeneous solvent system including a supernatant lipoprotein phase, said lipoprotein substance being at an acidic reaction in said anhydrous mixture, and separating said lipoprotein phase from other phases of said heterogeneous solvent system.

2. In a process for preparing a lipoprotein, wherein a proteinaceous substance and a fatty acid halide are reacted to form a lipoprotein substance, the steps of forming a substantially anhydrous mixture comprising said lipoprotein substance and an organic fat solvent having a specific gravity higher than that of the lipoprotein, infusing said anhydrous mixture with an anhydrous acid in an amount such that a free fatty acid and a salt are

formed therein in association with said lipoprotein, settling said mixture to form a heterogeneous solvent system including a supernatant lipoprotein phase, and separating said lipoprotein phase from other phases of said heterogeneous solvent system.

3. The process of claim 2 in which said fatty acid halide is an oleic acid halide.

4. The process of claim 2 in which said fatty acid halide is a fatty acid chloride.

5. The process of claim 2 in which said proteinaceous substance is gelatin.

6. In a process for preparing a lipoprotein, wherein a proteinaceous substance and a fatty acid halide are reacted in an aqueous medium containing an alkali having an alkali metal cation component to form a lipoprotein substance, the steps of dehydrating said lipoprotein substance, mixing the dehydrated lipoprotein substance with an organic fat solvent having a specific gravity higher than that of the lipoprotein, acidifying the resulting mixture with an anhydrous gaseous mineral acid to form a substantially anhydrous heterogeneous solvent system including a supernatant lipoprotein phase, and separating said lipoprotein phase from other phases in said heterogeneous solvent system.

7. The process of claim 6 in which said alkali metal cation component is a sodium component.

8. The process of claim 6 in which said anhydrous gaseous mineral acid is gaseous hydrochloric acid.

9. In a process for preparing a lipoprotein, wherein a

proteinaceous substance and a fatty acid chloride are reacted in an aqueous medium containing an alkalinizing agent having an alkali metal cation component and wherein the resulting condensation product is substantially dehydrated while being maintained at a pH of at least 6.5, the steps of mixing said dehydrated condensation product with an organic fat solvent having a specific gravity higher than that of said lipoprotein, infusing into the resulting solvent mixture an anhydrous organic solvent-dispersible acid in such amount as to adjust the pH of said condensation product to within the range of pH 4.5 to 5.5, and separating the supernatant lipoprotein phase from the other phases of said solvent mixture.

5 10 15 10. The process of claim 9 in which said organic fat solvent is ethylene dichloride.
